EUGÈNE VIOLET, OF LIMOGES, FRANCE.

PAPER-FASTENER.

1,355,629.

Specification of Letters Patent. Patented Oct. 12, 1920.

Application filed May 13, 1919. Serial No. 296,737.

To all whom it may concern:

Be it known that I, EUGÈNE VIOLET, a citizen of the Republic of France, and a resident of Limoges, in the Republic of France, 5 have invented certain new and useful Improvements in Paper-Fasteners, of which the following is a specification.

The present invention relates to an improvement in paper fasteners. One object 10 of the invention is to improve upon the construction and arrangement of the parts of a paper fastener in order to produce one capable of holding any number of sheets of paper firmly and which may be so operated 15 that the sheets of paper may be quickly and expeditiously placed in the fastener and as quickly and expeditiously removed therefrom, without opening up the pile of bound papers or disturbing the other sheets. An 20 other object of the invention is to produce a paper fastener of such construction that it is not necessary to perforate or cut the paper in any manner in order to provide for its effective holding or clamping or for the 25 alinement of the sheets held together. A further object of the invention is to produce a paper fastener of such construction that the thickness through the parts of the paper fastener is substantially no greater than 30 the thickness through the sheets of paper fastened together, irrespective of the number of sheets in the fastener. These and other objects of the invention are accomplished in the improved paper fastener illustrated 35 in the accompanying drawings, described in the following specification and particularly pointed out in the appended claims.

In the accompanying drawings illustrating 40 the preferred form of the invention, Figure 1 is a side elevation of the complete paper fastener as used in fastening or holding together several sheets of paper; Fig. 2 is a plan of the blank from which the holder 45 and binding springs are formed; Fig. 3 is a rear elevation of the fastener in open position; Fig. 4 is a section on an enlarged scale taken on the line 4—4 of Fig. 1; Fig. 5 is an end elevation of the fastener in use; 50 and Fig. 6 is a section taken on the line 6—6 of Fig. 1.

The improved paper fastener of the present invention as illustrated in the drawings comprises two jaws 9 and 10, which are 55 adapted to clamp the sheets of paper parallelly between them and relatively near their

margins. The jaws are formed from blanks, and each jaw consists of a single blank folded upon itself, so that one of the folds or flaps thereof is about one-half as wide as the other. When the blank has been thus folded, it is seen that one-half the width of the jaw is twice as thick as the other half. The working face of the clamping jaws is the face upon which the shorter fold 11 is located, that is to say, when the paper fastener is in use this face of the jaws will engage with the paper. The pressure exerted upon the jaws to bind or clamp the sheets of paper between them will be exerted upon this part of the jaws, so that the short fold of the jaws will be caused to exert a binding pressure upon the paper. The jaws will be so positioned upon the paper that the thin part of the jaws will extend toward the rear 75 margin of the paper. Only the forward or thicker half of the clamping jaws will thus exert any considerable pressure upon the paper, and the rear or thinner half of the jaws will not serve to compress the paper between them. In fact, the back margin of the paper will have a slightly fan-like appearance when viewed from the top or bottom ends of the pile of paper. This construction and mode of operation causes the fastener to clamp the sheets of paper tightly 80 without liability of their becoming loosened or detached. The part of the pile of paper subjected to the clamping pressure necessarily has a tendency to become thinner than 85 the parts of the paper not subjected to the clamping pressure. Consequently, the thickness of the pile of paper through its rear margin is slightly greater than the thickness through the clamped portion. 90 This fact aids in preventing the paper from being pulled from between the clamping jaws except by the exertion of considerable force. 95

In order to facilitate the alinement of the 100 sheets of paper used with the present fastener, each sheet may be conveniently provided with two or more cup-like depressions upon or near its rear margin. These depressions will be adapted to be engaged by 105 correspondingly shaped bosses 12 formed on the inner face of the short fold 11 of the clamping jaw 9 of the fastener. The depressions will be formed in the face side of the sheets of paper and consequently 110 there will be a correspondingly shaped boss or protuberance on the under sides of the

sheets of paper, and these bosses will be adapted to fit in holes 13 punched through the short fold 11 of the jaw 10. The bosses 5 12 and the holes 13 will, of course, be formed in their respective jaws before the latter are folded. When the jaws are in position in the fastener, the holes 13 will aline or register with the bosses 12. Not only does the embossing of the paper in this manner 10 and the provision of the bosses 12 and the holes 13 facilitate the alinement of the sheets of paper in the pile of paper fastened together temporarily by the fastener, but it also facilitates the alinement of the sheets 15 when they are bound together by the fastener for permanent insertion between covers, as the sheets of loose-leaf journals or ledgers, and the like. This construction also aids in preventing the sheets from being accidentally 20 removed when bound together by the fastener, and also facilitates the insertion and removal of the sheets of paper from the bound pile.

Each jaw is provided at the extremity of 25 its thickened portion with an axle or trunnion 15, upon which the jaw is adapted to pivot. When the clamping jaws are in position in the paper fastener, these trunnions are inserted in holes in the forward 30 ends of the arms 16, which constitute a part of the springs 17 for holding and operating the jaws. These arms project forwardly from the springs and the springs themselves are elongations of the body portion proper 35 or holder 18 of the paper fastener. The holes or bearings for the trunnions are made by rolling up the extremities 20 of the arms 16. It will be seen by reference to Fig. 2 that the spring portions 17 of the paper 40 fastener are formed by cutting a narrow slit 22 in the middle of each end of the plate or blank from which the body portion or holder of the fastener is formed. The longer this slit is the thicker the pile 45 of paper capable of being held by the fastener. Convenience, however, will dictate the thickness of the pile of paper to be held together by a single fastener. When the body portion or holder of the fastener has 50 been died out into the form shown in Fig. 2, it is folded upon its longitudinal axis. When the holder has been folded upon itself, it is ready for the clamping jaws, and these are inserted so that the short folds 11 55 will face each other. In order that the jaws may not revolve so that their thinner or rear ends will come together, each jaw is provided with an ear 24 projecting longitudinally and rearwardly from the middle of its thinner part, and these ears are adapted to strike or engage with the holder. Inasmuch as the axles or trunnions of the clamping jaws are located toward the front or inner edge of the jaws, the jaws will al-

ways have a tendency to remain in their 65 operative position.

The fastener is normally open, as shown in Fig. 3, the springs tending to hold the working surfaces of the jaws apart. In order to cause the jaws to exert a fastening or holding pressure upon the sheets of paper, each pair of springs is provided with a slide-ring 25, which is adapted to be moved outwardly upon the springs when the pile of paper is to be clamped. When, 70 however, a sheet of paper is to be removed from the clamped or held pile, the slide-rings are moved toward the middle of the holder, thereby releasing the tension on the springs and relieving the pressure the jaws 75 exert upon the paper. A stop 26 determines the inward movement of each of the slide-rings.

In order that the paper fastener may be adapted for use in connection with a pair 80 of covers or loose-leaf binder, as such covers are known in the art, the fastener is provided with slots 27 formed in the rear margin at the base of the springs, thereby adapting it for the rings or other means for 85 binding the pile of papers into the loose-leaf holder. The body portion or holder of the fastener itself may be provided with a series of holes for this purpose. It is thus seen that the paper fastener of the present 90 invention is adapted for use in connection with the ordinary forms of loose-leaf binder, and particularly those using either rings or other contrivances to fasten the sheets of paper into binders, with this advantage over 95 the previous methods of securing the sheets in the binders, namely, without the necessity of making holes in the paper itself.

It is obvious from the foregoing description what the mode of operation of the 105 improved paper fastener of the present invention is in use. The two slide-rings 25 are moved toward the middle of the holder against their stops 26, so that the springs will permit the clamping jaws to open 110 freely. The sheets of paper adapted to be held or bound together by the fastener will necessarily be shorter than the clamping jaws, or at least they will not have a greater length. The rear margins of the sheets of 115 paper will come substantially flush with the rear edges of the holding jaws. As the pile of paper held by the jaws grows in thickness, the jaws will, of course remain parallel or substantially parallel with the sheets of 120 paper, but the outer ends of the spring arms will spread out fan-like, with the holder necessarily in alinement with the middle of the pile of paper. It is seen that the rear edges of the pile of paper are 125 separated somewhat from the inner edge of the holder. This is for the purpose of permitting the inner edge of the holder to

progressively move nearer the rear edges of the pile of paper, as the pile grows in thickness and the forward ends of the arms of the springs are thereby forced farther 5 and farther apart. The mounting of the clamping jaws in the ends of the spring-arms, however, is such as to prevent the spring-arms from projecting any considerable distance beyond the sides of the pile 10 of paper. This enables the pile of paper held by the fastener to lie flat on the desk or table. It also enables several small piles of paper, each held or fastened together by the fastener of the present invention, to 15 be piled one on top of the other with the fasteners all at one side, without rendering this side much thicker than the other side. This is a feature of considerable importance, inasmuch as when a pile of paper is 20 made up of a considerable number of units, each fastened together by the fastener, the upper units will not have a tendency to slide off the piles, as is the case when ring-binders and the like are used. The paper 25 fastener of the present invention is not only adapted to hold or bind together sheets of paper for the purpose of keeping them temporarily segregated from other sheets, but is also adapted to permanently fasten 30 them together in loose-leaf binders adapted for the purpose. In either case, the bound sheets can be conveniently used in the form of a book, the sheets turning back as far as the inner edges of the clamped jaws. In 35 fact this method of binding or holding together loose sheets of paper closely resembles, in convenience, the binding together of sheets of paper permanently in a book, inasmuch as the sheets are always closely contiguous to each other, especially at the point 40 where they are bound together by the clamping jaws.

Having thus pointed out the features of the invention, it will be recognized that 45 the invention is not to be limited to the precise form shown in the drawings and described above, but that it may be embodied in other forms within the scope of the following claims.

50 What I claim as new and desire to secure by Letters-Patent is:—

1. A paper fastener comprising two jaws adapted to hold sheets of paper between them, springs having arms on the outer

ends of which the jaws are pivotally mounted 55 so as to swing on their longitudinal axis, said springs causing the jaws to exert a binding pressure upon the paper, and means for causing the springs to increase the pressure exerted by the jaws upon the paper. 60

2. A paper fastener comprising a pair of elongated jaws adapted to clamp sheets of paper between them, springs having arms arranged at right angles thereto, and bearings in the outer ends of the arms and extending longitudinally of the axis of the springs, the jaws being pivotally supported 65 in the bearings.

3. A paper fastener comprising two jaws adapted to hold sheets of paper between 70 them, a pair of arms for supporting each jaw so that it may swing on its longitudinal axis and parallelly to the other jaw and spring means for supporting the arms.

4. A paper fastener comprising a pair 75 of elongated jaws adapted to clamp sheets of paper between them, each jaw being formed from a blank folded upon itself so that one half the width of the jaw is substantially twice the thickness of the other 80 half and spring means for supporting the jaws so that the shorter folds of the jaws clamp the paper.

5. A paper fastener comprising a pair of jaws, a holder having spring ends, arms 85 projecting from the springs and provided with means for pivotally supporting the jaws, and stops on the jaws for preventing them from swinging past the arms.

6. A paper fastener comprising a pair of 90 elongated jaws, one part of which is substantially thicker throughout the length of the jaws than the other part, the clamping faces of the jaws being formed by the thickened portions thereof, a spring-holder for 95 supporting the jaws arranged so that the jaws will always be parallel irrespective of the thickness of the pile of paper interposed between them, and means for increasing the pressure exerted by the jaws upon 100 the paper.

7. A paper fastener comprising pivotally mounted clamping jaws, a holder having spring means for supporting the jaws and being provided with apertures adapted to receive binding means for securing the fastener in a loose-leaf binder. 105
